TOOTHBRUSH HAVING A TRAPEZOIDAL TRANSVERSE HEAD

Filed Jan. 27, 1947

UNITED STATES PATENT OFFICE

2,603,806

TOOTHBRUSH HAVING A TRAPEZOIDAL
TRANSVERSE HEAD

Christian Kisky, Lake Grove, Oreg.

Application January 27, 1947, Serial No. 724,631

2 Claims. (Cl. 15—167)

1

My present invention relates to a new and improved tooth brush.

An object of the present invention is to provide a tooth brush which will encourage the use of the proper method of brushing teeth. It is an established dental principle that teeth should be brushed vertically or in line with the longitudinal axes thereof as distinguished from the ordinary practice of brushing teeth horizontally or across the surfaces thereof in line with the gums. Horizontal brushing, particularly when a stiff brush is used, may result in rapid deterioration of the enamel of the teeth, particularly at the thinly enameled portion thereof adjacent the gums. Furthermore, such horizontal brushing serves to pack food and other particles between the teeth rather than to clean the dental crevices, thus causing the accumulation of deposits wherein caries-forming bacteria may flourish, or enamel-destroying acids develop. The present invention is designed to promote the use of the proper vertical brushing motion due to the inherent characteristics of the brush.

A further object of the present invention is to provide a brush wherein the bristles are mounted upon a head extending transversely of an elongated handle, thus providing a structure capable of reaching extremely remote and ordinarily inaccessible portions of the teeth and permit the brushing thereof with the proper vertical brushing movement.

A further object of the present invention is to provide a brush wherein the bristles are so inclined with respect to the elongated handle which fits within the palm of the brushing hand that they are caused to approach the teeth and gums at an approximate angle of 45 degrees thereto whereby the bristles will yield and bend rather than jab into the tissues of the gums. The advantage of such a construction is that the gums are protected from inflammation and puncturing by stiff and sharp bristles and thus the opportunity for gum deteriorating bacteria to penetrate into the tissues of the gum is lessened.

A further object of the present invention is to provide a tooth brush having the foregoing characteristics, objects and advantages wherein the handle portion and the transverse heads or bristle carrying members are joined by relatively narrow neck portions permitting the entry of bristle carrying portions of the tooth brush into all remote corners of the mouth without excessively straining or stretching the lips of the user.

A further object of the present invention is to provide a brush having the foregoing objects and

2

advantages wherein the bristle tufts are provided in a plurality of rows, the bristles of one row being staggered with respect to the bristles of the other row so that regardless of the positioning of the tooth brush at least one bristle tuft will enter each crevice between the teeth as the brush is moved vertically across the surfaces thereof.

The objects and advantages of the present invention will be more fully apparent from a study of the following specification taken in connection with the accompanying drawings wherein like numerals refer to like parts throughout.

In the drawings Fig. 1 is a view in side elevation of a brush made in accordance with the present invention and having a single head thereon;

Fig. 2 is a plan view of the brush of Fig. 1;

Fig. 3 is a side elevation of a double-ended brush made in accordance with the present invention;

Fig. 4 is a plan view of the brush of Fig. 3;

Fig. 5 is a side elevation of a modified form of double-ended brush;

Fig. 6 is a plan view of the brush of Fig. 5;

Fig. 7 is a view showing a partial section through the incisor bearing portion of the maxilla of a brush user and illustrating the functioning of the present tooth brush in brushing the labial and lingual surfaces of the teeth;

Fig. 8 is a partial view in side elevation of the jaws of a person using the present invention to brush behind the rearmost molar of the upper jaw;

Fig. 9 is a similar view showing the brush of the present invention in use to brush the labial surfaces of the molars; and

Fig. 10 is a similar view illustrating the arrangement of the bristle tufts whereby assurance is achieved that at least one bristle tuft will operate upon each crevice between adjoining pairs of teeth.

In one sense the present invention is an improvement upon my prior Patent No. 2,378,641 issued June 19, 1945, reissued as Reissue No. 22,938, reissued November 25, 1947. In many other senses, however, the present invention bears but little relation to the foregoing patent and application for reissue thereof.

Referring to Figs. 1 and 2 there is disclosed a tooth brush comprising an elongated handle 10 having substantially planar configuration including an upper surface 11 and a lower or rear surface 12. The handle is preferably of considerable width with respect to its thickness so that

the planar surfaces thereof 11 and 12 will be located within the palm of the user and thus serve to aid in locating the relationship of the bristles to the teeth.

At one end of the handle 10 there is provided a bristle bearing head 14 which is substantially planar in general outline and extends transversely of the handle 10. The upper or bristle bearing surface 15 of the head lies in a plane and, in this modification, the plane thereof is substantially parallel to the planes of the surfaces 11 and 12 of the handle 10. The head 14 is joined to the handle 10 at the end of the planar surface 12 of the rear surface of the handle 10, and the edges of the handle 10 are convergent adjacent the junction to provide a relatively narrow neck portion 16. The surface 15 of the head is provided with a pair of rows of bristle tufts 17, the axes of the bristle tufts being substantially parallel and inclined forwardly at an acute angle to the surface 15. It will be noted also that the surface 11 of the handle 10 is preferably directed downwardly at the junction of the handle with the head so as to decrease the thickness of the neck portion 16.

Since this tooth brush is designed with a single head, which head must serve to brush both the lingual and labial surfaces of the teeth, a compromise angular relationship of the various parts between that most desirable for lingual surfaces and that most desirable for labial surfaces is arranged. It will be noted that the axes of the bristle tufts are substantially parallel to a plane A extending upwardly and outwardly from the plane B of the rear surface 12 of the handle at an angle of substantially 50 degrees so that the bristle tufts are at an angle of substantially 40 degrees to a plane C normal to the longitudinal axis of the handle. The bristle tufts 17 terminate in a plane D which is substantially parallel to the plane E coincident with the surface 15, which in this case is substantially parallel and midway between the planes D and B.

Referring to Figs. 3 and 4 there is disclosed a handle 20 of substantially planar characteristics in that it is broader than it is wide so that the palm-fitting portion thereof will locate the bristle bearing surfaces. The upper surface 21 and the lower surface 22 extend generally in planes but are provided with transverse corrugations forming gripping surfaces to prevent slippage of the brush handle when the hands are wet.

One end of the brush is provided with a lingual bristle head 23 and the opposite end of the brush is provided with a labial bristle head 24, each of the heads being substantially planar and extending transversely of the longitudinal axis of the handle 20, and each of the heads including a bristle bearing planar surface lying at an acute angle to the plane of the handle.

The lingual head 23 has a bristle surface 25 extending upwardly from the handle portion at an angle of substantially 30 degrees thereto as indicated by the plane F. The surface 25 carries a pair of transverse rows of bristle tufts 26, the tips of which lie substantially in a plane G parallel to the plane F. The bristle tufts 26 are substantially parallel to each other, extend outwardly away from the handle in the direction of the handle and are parallel to a plane H which is inclined outwardly at substantially 15 degrees to the plane I normal to the longitudinal axis of the handle. Therefore, the planes F and G are at an angle of substantially 45 degrees to the plane H.

The labial head 24 has a bristle-bearing surface 27 facing outwardly from the handle portion at an angle of substantially 20 degrees to a prolongation of the longitudinal axis of the handle as indicated by the plane J. The surface 27 carries a pair of transverse rows of bristle tufts 28, the tips of which lie substantially in a plane K parallel to the plane J. The bristle tufts 28 are substantially parallel to each other, extend outwardly away from the handle in the direction of the handle and are parallel to a plane L which is inclined outwardly at substantially 65 degrees to a plane M normal to the longitudinal axis of the handle. Therefore, the planes J and K are at substantially 45 degrees to the plane L.

Referring to Figs. 5 and 6 there is disclosed a handle 30 of substantially planar characteristics having a planar upper surface 31 and a planar lower surface 32. One end of the brush is provided with a lingual bristle head 33 and the other end of the brush is provided with a labial bristle head 34, each of the heads being substantially planar and extending transversely of the longitudinal axis of the handle 30 and each of the heads including a bristle-bearing planar surface lying at an acute angle to the plane of the handle.

The lingual head 33 has a planar bristle surface 35 extending upwardly from the handle portion at an angle of substantially 20 degrees thereto as indicated at the plane N. The surface 35 carries a pair of transverse rows of bristle tufts 36, the tips of which lie substantially in a plane O parallel to the plane N. The bristle tufts 36 are substantially parallel to each other, extend outwardly away from the handle in the direction of the handle and are parallel to a plane P which is inclined outwardly at substantially 15 degrees to a plane Q normal to the longitudinal axis of the handle. Therefore, the planes N and O are at an angle of substantially 55 degrees to the plane P.

The labial head 34 has a bristle surface 37 facing away from the handle portion at an angle of substantially 10 degrees to a prolongation of the axis of the handle as indicated by the plane R. The surface 37 carried a pair of transverse rows of bristle tufts 38, the tips of which lie substantially in a plane S parallel to the plane R. The bristle tufts are substantially parallel to each other, extend outwardly away from the handle in the direction of the handle and are parallel to a plane T which is inclined upwardly at substantially 60 degrees to the plane U normal to the longitudinal axis of the handle. Therefore, the planes R and S are at an angle of substantially 40 degrees to the plane T.

It will be seen that in the brush illustrated in Figs. 1 and 2 the head 14 is substantially rectangular in outline while in the brushes illustrated in Figs. 3 to 6 inclusive the bristle-bearing heads are provided with divergent end surfaces so that the outer edges thereof are wider than the inner edges thereof. With respect to the first modification the inner row of bristles contains the same number of bristle tufts as the outer row, while in each of the other bristle heads there is one less bristle tuft on the inner row than there is on the outer row. Also the first modification has the bristle tufts in line with each other in the direction of the handle, whereas in all other modifications the bristle tufts in one row are staggered with respect to the bristle tufts in the other row so that one bristle tuft covers

the space between pairs of bristle tufts in the other row in the direction of the handle.

It will be noted in the modifications disclosed in Figs. 3 to 6 inclusive that the lingual bristle head is smaller than the labial bristle head, particularly with respect to the width thereof. The heads at both ends preferably taper inwardly toward the handle portion so that the neck portions of the brush are relatively narrow in all dimensions.

The bristle-bearing head of the modification of Fig. 1 and the adjoining handle portion thereof is preferably so shaped that the rear surface opposite to the bristle-bearing surface 15 slopes upwardly away from the plane of the rear surface 12 of the handle. The curvature thereof is irregular but a preferred characteristic of the curve is that it shall lie within or substantially conform to the surface of a cylinder of revolution V having as its axis the line W formed by the intersection of the plane D passing through the tips of the bristle tufts and the plane C normal to the end of the planar portion of the rear surface 12 of the handle. Also the tips of the outermost rows of bristles 17 touch or lie within this imaginary cylindrical surface V. The same characteristic will be apparent with respect to each of the other bristle heads illustrated. The head 23 has its rear surface substantially conforming to or lying within an imaginary cylinder of revolution X having as its axis a line Y formed by the intersection of the planes G and I. The rear surfaces of the head 24 and the adjoining portion of the handle 20 lies within an imaginary cylinder of revolution Z having as its axis the line a formed by the intersection of the plane K passing through the bristle tips and the plane M normal to the longitudinal axis of the handle at the end of the substantially planar portion of the rear surface thereof. The head 33 is formed to lie within or substantially conform to the surface of a cylinder of revolution b having as its axis the line c formed by the intersection of the plane O and the plane Q. The rear surface of the head 34 lies within an imaginary cylinder of revolution d having as its axis the line e formed at the intersection of the plane S passing through the bristle tips and the plane U normal to the handle at the end of the rear surface thereof.

Each of the imaginary cylinders of revolution is substantially tangent to the rear surface of the handle. It is immaterial to the present invention that the surfaces should exactly follow this imaginary cylindrical surface but they preferably closely approximate such a surface so that, as will be seen in Figs. 7, 8, 9 and 10, the brush heads may be fitted into close quarters such as represented by the space between the lips and the gums or the space behind the last molars and still be manipulated.

As seen in Fig. 7 a brush having a labial head, such as a head 24 of Fig. 3 will fit the space between the lips and the gums and will naturally cause the bristle tufts to approach the gums at an angle of substantially 45 degrees thereto so that, rather than be jabbed into the tissues of the gums, the bristles will bend back and lie along the surfaces thereof. This angle may be greater than 45 degrees but the lip discourages the tipping of the handle outwardly until the angle would become less than 45 degrees. The wider surface of the head is possible due to the conformation of the jaws and the lips or cheeks so that a greater number of bristles may be carried.

Fig. 7 also illustrates the use of a lingual head such as the head 33 of the brush illustrated in Fig. 5. It will be seen that the inclination of the bristles at the angle at which the brush would be held is substantially 45 degrees to the surfaces of the gums when the bristles approach the gums in normal usage.

Fig. 8 illustrates the use of a lingual bristle head such as the head 33 in reaching behind the rearmost molars. The natural inclination of the handle is such that again the bristles approach the gums at an angle of 45 degrees or greater. Whether the handle be inserted so as to lie within the teeth or between the teeth or outside 15 of the teeth is relatively immaterial since the laterally extending portions of the head provide means for reaching the ordinarily inaccessible portions of the rear molars.

Fig. 9 illustrates the use of a labial head such as the head 34 in brushing the labial surfaces of the molars, showing that the narrow neck at the junction of the head and the handle facilitates the entry of bristle tufts to the surfaces of the teeth without excessively stretching the lips or cheeks.

Fig. 10 illustrates a bristle head, such as the head 34, brushing the labial surfaces of molars and bicuspids and showing that no matter where the head is positioned there will be at least one bristle tuft 38 in line with the grooves between each pair of teeth due to the staggering of the bristle tufts in the rows.

In Figs. 7, 8, 9 and 10 there are directional arrows showing the direction of use or motion of the brush in brushing the teeth. It will be apparent that the transverse heads and angular arrangements thereof encourage the proper vertical and downward brushing motion on the upper teeth. It will also be apparent that in most cases 40 continuation of the same movement will cause a vertically downward brushing motion across the lower teeth. It is more desirable that the angularity of the brush handle be reversed and the lower teeth be brushed vertically upward. However, even though a person may be inclined to omit reversing the tooth brush and continue a vertical stroke downward across the lower teeth such a motion is preferable to the horizontal scrubbing which is encouraged by the conventional tooth brush.

I have herein illustrated, for the most part, bristle tufts having each bristle of the same length as all others. However, in Fig. 3, I have illustrated that the bristle tufts 26 may be trimmed to form ridges running transversely of the handle. The trimming could be in a direction longitudinal of the handle if desired, or if a proper process could be developed each bristle tuft might be conically trimmed. However, it is 55 a feature of my tooth brush that all bristles could be of the same length and yet be just as satisfactory as ridged or pointed bristle tufts. However, if desired any of the heads herein illustrated 60 might have bristle tufts of modified shape.

Likewise it is to be noted that in Figs. 1 and 2 I have illustrated a bristle head which is a compromise head. However, it will be obvious that a single tooth brush could be provided with a head such as the head 23, or a head such as the head 24, if desired and that the ends thereof could be divergent, and its surface sloped, and 70 staggered tufts be formed thereon, provided that the other advantageous features as illustrated and described were incorporated in the single head.

Having illustrated and described preferred em-

bodiments of my invention it should be apparent to those skilled in the art that modifications in detail and arrangement thereof are permissible. All such modifications as come within the true spirit and scope of the appended claims are considered to be a part of my invention.

I claim:

1. A tooth brush comprising an elongated handle, a narrow bristle base extending transversely of said handle at the end thereof and projecting laterally from both sides of said handle, and a plurality of parallel bristle tufts extending from said bristle base, said bristle base having the general shape of a trapezoid with its shorter parallel side toward said handle and its longer parallel side forming the forward edge of the tooth brush, the bristle bearing surface of said bristle base being a flat surface inclined to said handle, the opposite surface of said bristle base being rounded toward the longer parallel side of the bristle bearing flat surface, and said bristle tufts being inclined toward the longer parallel side of the bristle bearing flat surface and terminating in a plane parallel to said flat surface.

2. A tooth brush comprising an elongated handle, a narrow bristle base extending transversely of said handle at the end thereof and projecting laterally from both sides of said handle, and a plurality of parallel bristle tufts extending from said bristle base, said bristle base having the general shape of a trapezoid with its shorter parallel side toward said handle and its longer parallel side forming the forward edge of the tooth brush, the bristle bearing surface of

said bristle base being a flat surface inclined to said handle, the opposite surface of said bristle base being inclined upwardly toward said longer parallel side of the bristle bearing surface and forming therewith an acute angle, and said bristle tufts being inclined toward said longer parallel side of the bristle bearing flat surface and terminating in a plane parallel to said flat surface.

CHRISTIAN KISKY.
